CLAIM

The ornamental design for a decorative wall block, as shown and described.

DESCRIPTION

The figure is a perspective view of a decorative wall block showing my new design, it being understood that the left end side is a mirror image of the right end side shown and that the bottom side is a mirror image of the top side shown. FIG. 1 is a perspective view of a decorative wall block showing my new design, it being understood that the left end side is a mirror image of the right end side shown and that the bottom side is a mirror image of the top side shown. FIG. 2 is an enlarged top and bottom plan view; FIG. 3 is an enlarged left and right side elevation view; and, FIG. 4 is an enlarged front elevation view.

The surface(s) or portion(s) of the article not shown in the drawing or described in the specification form(s) no part of the claimed design.
